SYSTEM AND APPARATUS FOR RELEASE
OF FLUIDS

Daniel Mapes, Upper Montclair, N. J., assignors
to Walter Kidde & Company, Inc., New York,
N. Y., a corporation of New York

Application October 21, 1931, Serial No. 570,102

11 Claims. (Cl. 169—11)

In another application for Letters Patent of the United States, Serial No. 278,009, filed May 15th, 1928, there is covered a cutter valve designed particularly for the release of carbon dioxide under pressure for the purpose of extinguishing fire, although capable of application for other purposes. In that application a single cutter valve is shown so designed that a plurality of such valves can be operated by fluid pressure from an external source. In accordance with that invention the plurality of cutter valves is connected in parallel for substantially simultaneous operation by pressure from a source of control pressure, and although the pressure released from the controlled containers is added to the pressure from the source of control pressure and assists the latter in actuating any cutter valve which has failed to operate sooner, the system is not so designed as to insure operation of all of the cutter valves. In the present case it is sought to cover a plurality of cutter valves of the general type referred to in combination with a plurality of containers of fluid under pressure, the parts being so designed, constructed and related that all of the cutter valves of a battery of containers may be operated through the release of a fluid under pressure from a single control container or other source and so that the fluid released from the control container can act on only one cutter valve of a battery at one time, after the operation of which the control fluid is released to operate another cutter valve in the battery, et cetera.

It is accordingly an object of the present invention to provide a pressure-operated cutter valve which is positive in operation, yet simple in construction.

It is a further object of the invention to provide a system for operating a plurality of pressure-operated cutter valves having the same degree of positiveness of operation as a single cutter valve in accordance with this invention.

Another object is to provide a system which is initially operable only by pressure from a source of control pressure and in which the accidental release of pressure from any controlled container, as by development of excessive pressure with consequent release of pressure through the container closure, will not cause operation of the system.

Another object is to provide a system in which the cutter valves of a plurality of containers are operatively connected in series in a battery, so that the control pressure acts on each pressure-operated cutter valve in succession but only upon one cutter valve of the battery at one time.

Another object is to provide a system in which

the cutter valves are connected in series in a plurality of batteries, each connected to the source of control pressure whereby failure of a cutter valve in any battery to operate, as by reason of mechanical defects therein, will not affect the operation of the cutter valves in any other battery.

Further objects, not specifically enumerated above, will be apparent as the invention is described in greater detail in connection with the accompanying drawings, wherein:

Figure 1 is a perspective view of a complete system in accordance with the present invention, showing a single control container operatively connected to a plurality of batteries of controlled containers provided with pressure-operated cutter valves of special construction.

Figure 2 is a view in vertical, central section of one of the release devices or cutter valves shown in Figure 1.

Figure 3 is a view similar to Figure 2, on a somewhat smaller scale, but showing a different embodiment of the invention.

In Figure 1 of the drawings there are represented at 1 containers of carbon dioxide from which fluid under pressure is discharged through 2 a pipe 2 (see Figure 2) which is extended in each container near to the bottom. To each container is secured one member 3 of a suitable coupling into which the pipe 2 may be threaded, such coupling member being provided at 4 with a seat 30 for a sealing disc 5 and sealing gasket 6 held in place by a thimble 7. For convenience in manufacture and assembling a second coupling member 8 is formed separately from the coupling member 3 and may be secured thereto by threads 9 engaging cooperating threads on the coupling member 3. This coupling member is chambered, as at 10, to receive with a close-working fit, as at 11, a piston member 12.

Actuated by the piston 12 is a device 13 by which the sealing disc 5 is to be ruptured. In the construction shown this rupturing device is a tubular cutter extending within a passage 14 to permit the fluid from the container 1, when released, to pass into the chamber 15 and thence through a port 16 into one of the discharge lines 17 which, as shown in Figure 1, connect the outlet ports 16 of the release devices with the inlet ports 18 of the adjacent release devices. In the construction shown the tubular cutter 13 is forced into an extension or reduced portion 19 of the piston 12. It is also shown as bevelled and sharpened at its lower end, as at 20, so that, when driven downward by movement of the piston 12, it will cut out the disc 5 and allow the fluid to

escape from the container 1 into the discharge line 17. At 21 is shown a coiled spring for normally sustaining the piston 12 in its highest position.

From the foregoing description it will be apparent that the piston 12 normally closes off communication between the inlet port 18 and the outlet port 16, but when the actuating pressure is applied through the inlet port 18 the piston 12 is forced downward, carrying with it the hollow tubular cutter 13 which ruptures the sealing disc 5 and permits the contents of the container 1 to be released through the hollow tubular cutter and the passage 14. By this time the piston 12 has uncovered the outlet port 16 so that both the actuating fluid and the fluid released from the container 1 pass through the outlet port 16 and the discharge line 17 to the inlet port 18 of the adjacent cutter valve. The apparatus is preferably so designed that the rupturing of the sealing disc 5 is effectively completed before the piston 12 uncovers the port 16 and permits the actuating fluid to proceed to the adjacent cutter valve. In this manner a positive pressure-operated cutter valve is obtained in accordance with the present invention.

It will be apparent that development of excessive pressure within the control container 1 will cause rupturing of the sealing disc 5, which is normally designed as a safety disc, and in order to prevent operation of the piston 12 by the pressure fluid thus accidentally released from the container 1, the piston is provided with an upwardly extending projection 22 which has a close-working fit, as at 23, with a bored-out portion of a sealing nut 24 adapted to close the upper portion of the coupling member 8. This projection 22 is also preferably formed to engage the bore in the sealing nut 24 along the surface 25. With this construction there is no possibility of pressure accidentally released from the container 1 acting on the upper surface of the piston. At the same time the pressure thus accidentally released is permitted to escape through ports 26 in the hollow tubular cutter 13 and the lower piston extension 19 into the chamber 10 and then to the atmosphere through ports 27 in the wall of the coupling member 8. With this construction there is an additional safeguard against accidental operation of the piston as the pressure in the chamber 10 acts on the entire underneath surface of the piston and maintains it in its uppermost position.

In order to prevent escape of the fluid through the ports 26 when the cutter valve is intentionally operated, the ports 26 are designed to recede within the bore 28 in the lower part of the coupling member 8, this bore being engaged with a close-working fit by the lower piston extension 19 so that fluid released from the container 1 cannot reach the chamber 10 and oppose the operative movement of the piston. However, the ports 27 will permit the escape of any fluid leaking past the lower piston extension 19, as well as any fluid leaking from above past the piston 12, and will at the same time prevent the building up of back-pressure by the air contained within the chamber 10 beneath the piston.

Referring again to Figure 1, a source of control pressure is shown as a container 29 provided with a valve 30 operable by a control handle 31 connected to the valve by a flexible cable 32 passing around a pulley 33, these controlling elements being old and thus forming no part of the present invention. The fluid outlet of the

valve 30 is shown connected by piping 34 to a fitting 35 and a fitting 36. Four batteries of three of the containers 1 are shown connected to the fittings 35 and 36 by connecting pieces 37, the outlet port 16 of each container in a battery being connected to the inlet port 18 of the adjacent container and the inlet port 18 of the first container in a battery being connected by the piece 37 to the piping 34. The outlet ports of the last containers in each group are connected to a common manifold 38 by the connecting pipes 39 and 40. When the control fluid, which is of the same nature as the fluid to be released from the controlled containers 1, is released from the container 29 by the opening of the valve 30, the pressure of the control fluid acts upon the pistons of the first containers in each battery, and as soon as the pressure has actuated the cutter valves of these containers, it is released through the outlet ports of these containers into the inlet ports of the second containers, this manner of operation continuing until the last containers have been released, whereupon both the control fluid and the released fluid are discharged through the common manifold 38.

With this arrangement, positive operation of the various pressure-operated cutter valves is insured and if for any reason, such as a mechanical defect in one of the cutter valves, a cutter valve in any battery should fail to operate, the operation of the other batteries will not be affected.

The amount of fluid discharge lost by the failure of any cutter valve in a battery to operate will depend upon the position of the cutter valve in the battery. For example, if the cutter valve of the last container of a battery of three containers fails to operate, only the fluid from that container will be lost for fire extinguishing or other purposes, as the fluid released from the first and second containers will be discharged back through the connections of the other batteries.

It should also be noted that the operation of the various batteries can only be initiated by the control fluid, as the construction of the individual cutter valves, whereby accidental release of fluid from any controlled container cannot operate the piston of that container, likewise prevents operation of the cutter valves of any other containers in the same battery or in other batteries.

Referring now to Figure 3, the parts bearing the same reference characters as in Figure 2 are of the same construction and have the same functions as the parts in Figure 2 and further description of these elements is unnecessary. The chief difference of Figure 2 is in the construction of the piston 12' and in the arrangement of the inlet port 18' and the outlet port 16'. In this construction the outlet port 16' is arranged in a sealing nut 41 closing the upper portion of the coupling member 8 so as to form the chamber 15. A cage is threaded into the sealing nut 41 so as to form a gas-tight joint and is provided at its lower end with ports 43. The lower surfaces 44 and 45 of the cage 42 are adapted to engage corresponding surfaces of a bored-out portion of the piston 12' with a close-working fit, so as to produce a substantially gas-tight seal. The circumference of the piston 12' is grooved at 46 so as to be releasably engaged by the spring-pressed ball 47 of a commercially obtainable catch 48 which is supported in the 70

wall of the coupling member 8 by a special bushing 49.

When the actuating pressure is admitted to the coupling member 8 through the inlet 18', it acts upon the upper surface of the piston 12' which advances the hollow tubular cutter 13' rupturing the sealing disc 5 and releasing the contents of the container 1. The parts are preferably so designed that the rupturing of the sealing disc 5 is effectively completed before the piston 12' uncovers the ports 43. The continued downward movement of the piston then completely uncovers the ports 43 and both the actuating fluid and the released fluid flow out through the ports 43 and the outlet port 16' to the inlet port 18' of the adjacent cutter valve.

It will accordingly be noted that the construction in accordance with Figure 3 can be employed in the general arrangement shown in Figure 1 equally as well as the construction shown in Figure 2 and in connection with both of these constructions it should be noted that it is preferable to design the inlet and outlet ports so as to take the combined flow of the medium released from all the containers in a single battery without throttling of flow.

It will accordingly be seen that I have invented a novel system of operating fluid releasing devices together with certain novel constructions of such devices and, while the present invention has been described with specific reference to the accompanying drawings, it is not to be limited, save as defined in the appended claims.

I claim as my invention:

1. In combination a fluid container having an opening and a closure for the opening, a body forming a chamber, an operating member in the form of a piston in said chamber, an inlet for admitting an operating fluid into the chamber above the operating member to actuate the same, an opening member associated with said operating member, said opening member being operable by said operating member to open said closure, an outlet port normally closed off by the operating member from the space above the operating member and uncovered by movement thereof to release the operating fluid only after the opening of the closure member has been effectively completed, and a passage for connecting the space above the closure with the space above the operating member after the latter has been operated, said passage being formed in said opening member and closed by a portion of the body when the operating member is in its inoperable position, said passage being open when the operating member is moved to a position where the opening member opens the closure, whereby the fluid released from the container may also be discharged through the outlet port after it has been uncovered by the operating member.
2. In combination a fluid container having an opening and a closure for the opening, a body forming a chamber, an operating member in the form of a piston in said chamber, an inlet for admitting an operating fluid into the chamber above the operating member to actuate the same, an opening member associated with said operating member, said opening member being operable by said operating member to open said closure, an outlet port normally closed off by the operating member from the space above the operating member and uncovered by movement thereof to release the operating fluid only after the opening of the closure member has been effectively completed, a
- passage connecting the space above the closure with the space above the operating member when the latter has been operated, said passage being formed in said opening member and said operating member, whereby the fluid released from the container may also be discharged through the outlet port after it has been uncovered by the operating member, and means to prevent operation of the operating member by the fluid from the container when accidentally released by reason of the development of excessive pressure in the container, said last named means shutting off access between the container and the space above the operating member by reason of the development of excessive pressure in the container, said last named means shutting off access between the container and the space above the operating member when the operating member is in its un-operated position, and means to permit escape of the fluid when accidentally released.
3. In combination a fluid container having an opening and a closure for the opening, a body forming a chamber, an operating member in the form of a piston in said chamber, an inlet for admitting an operating fluid into the chamber above the operating member to actuate the same, an opening member associated with said operating member, said opening member being operable by said operating member to open said closure, an outlet port normally closed off by the operating member from the space above the operating member and uncovered by movement thereof to release the operating fluid only after the opening of the closure member has been effectively completed, a passage connecting the space above the closure with the space above the operating member when the latter has been operated, said passage being formed in said opening member and said operating member, whereby the fluid released from the container may also be discharged through the outlet port after it has been uncovered by the operating member, and means to prevent operation of the operating member by the fluid from the container when accidentally released by reason of the development of excessive pressure in the container, said last named means shutting off access between the container and the space above the operating member by reason of the development of excessive pressure in the container, said last named means shutting off access between the container and the space above the operating member when the operating member is in its un-operated position, and means to prevent operation of the operating member by the fluid from the container when accidentally released by reason of the development of excessive pressure in the container, said last named means shutting off access between the container and the space above the operating member when the operating member is in its un-operated position.
4. In combination a fluid container having an opening and a closure for the opening, a body forming a chamber, an operating member in the form of a piston in said chamber, an inlet for admitting an operating fluid into the chamber above the operating member to actuate the same, an opening member associated with said operating member, said opening member being operable by said operating member to open said closure, an outlet port normally closed off by the operating member from the space above the operating member and uncovered by movement thereof to release the operating fluid only after the opening of the closure member has been effectively completed, a passage connecting the space above the closure with the space above the operating member when the latter has been operated, said passage being formed in said opening member and said operating member, whereby the fluid released from the container may also be discharged through the outlet port after it has been uncovered by the operating member, and means to prevent operation of the operating member by the fluid from the container when accidentally released by reason of the development of excessive pressure in the container, said last named means shutting off access between the container and the space above the operating member when the operating member is in its un-operated position, and means to permit escape of the fluid when accidentally released.
5. In combination a fluid container having an opening and a closure for the opening, a body

forming a chamber, an operating member in the form of a piston in said chamber, an inlet for admitting an operating fluid into the chamber above the operating member to actuate the same, an opening member associated with said operating member, said opening member being operable by said operating member to open said closure, an outlet port normally closed off by the operating member from the space above the operating member and uncovered by movement thereof to release the operating fluid only after the opening of the closure member has been effectively completed, a passage connecting the space above the closure with the space above the operating member when the latter has been operated, said passage being formed in said opening member and said operating member, whereby the fluid released from the container may also be discharged through the outlet port after it has been uncovered by the operating member, means to prevent operation of the operating member by the fluid from the container when accidentally released by reason of the development of excessive pressure in the container, said last named means shutting off access between the container and the space above the operating member when the operating member is in its un-operated position, and means to permit escape of the fluid when accidentally released, said last named means comprising a passage connecting the container above the closure with the chamber beneath the operating member and a passage therefrom to the atmosphere.

6. In combination a fluid container having an opening and a closure for the opening, a body forming a chamber, an operating member in the form of a piston in said chamber, an inlet for admitting an operating fluid into the chamber above the operating member to actuate the same, an opening member associated with said operating member, said opening member being operable by said operating member to open said closure, an outlet port normally closed off by the operating member from the space above the operating member and uncovered by movement thereof to release the operating fluid only after the opening of the closure member has been effectively completed, a passage connecting the space above the closure with the space above the operating member when the latter has been operated, said passage being formed in said opening member and said operating member, whereby the fluid released from the container may also be discharged through the outlet port after it has been uncovered by the operating member, means to prevent operation of the operating member by the fluid from the container when accidentally released by reason of the development of excessive pressure in the container, said last named means shutting off access between the container and the space above the operating member when the operating member is in its un-operated position, and means to permit escape of the fluid when accidentally released, said last named means comprising a passage connecting the container above the closure with the chamber beneath the operating member and a passage therefrom to the atmosphere, said last named passage likewise serving to prevent the building up of effective resistance to the operative movement of the operating member.

7. In combination: a primary receptacle carrying a fluid under pressure, primary fluid retaining means for retaining said fluid in said receptacle, a delivery means into which said fluid is delivered when it is released, and primary op-

erating means for operating said primary fluid retaining means in a manner to release the fluid from said primary receptacle; and a plurality of secondary receptacles carrying a fluid under pressure, each having a chambered body member, a secondary fluid retaining means associated with each said chambered body member for retaining said fluid in each said secondary receptacle, a secondary operating means for operating each said secondary fluid retaining means in order to release the fluid from each said secondary receptacle, and a fluid operated means mounted in the chamber of each said body member for actuating each said secondary operating means; each said chambered body member having an inlet for admitting an operating fluid into the body member to a surface of the fluid operated means to actuate the same, an outlet passage in the body member normally closed off from the surface of the operating member to which the operating fluid is admitted and adapted to be opened thereto by movement of the operating member to release the operating fluid to the outlet only after the opening of the closure member has been effectively completed, and a normally closed fluid conducting passage adapted to be opened by movement of the operating member to connect the space above the closure with the outlet; said sec-

ondary receptacles being operatively connected in a plurality of groups, the outlets and inlets of the secondary receptacles in each group being operatively connected in succession for fluid conduction and the inlets of the head receptacles in each group being connected to the said delivery means in parallel; whereby upon release of fluid from the primary receptacle the fluid operated means directly connected to the delivery means in parallel are each acted upon by a portion of the fluid released from the primary receptacle, and each succeeding fluid operated means in a group is acted upon in succession both by a portion of the fluid released from the primary receptacle and the fluid released from the preceding receptacle or receptacles in the same group.

9. In combination: a primary receptacle carrying a fluid under pressure, primary fluid retaining means for retaining said fluid in said receptacle, a delivery means into which said fluid is delivered when it is released, and primary operating means for operating said primary fluid retaining means in a manner to release the fluid from said primary receptacle; and a plurality of secondary receptacles carrying a fluid under pressure, each having a chambered body member, a secondary fluid retaining means associated with each said chambered body member for retaining said fluid in each said secondary receptacle, a secondary operating means for operating each said secondary fluid retaining means in order to release the fluid from each said secondary receptacle, and a fluid operated means mounted in the chamber of each said body member for actuating each said secondary operating means; each said chambered body member having an inlet for admitting an operating fluid into the body member to a surface of the fluid operated means to actuate the same, an outlet passage in the body member normally closed off from the surface of the operating member to which the operating fluid is admitted and adapted to be opened thereto by movement of the operating member to release the operating fluid to the outlet only after the opening of the closure member has been effectively completed, and a normally closed fluid conducting passage adapted to be opened by movement of the operating member to connect the space above the closure with the outlet; said secondary receptacles being operatively connected in a plurality of groups, the outlets and inlets of the secondary receptacles in each group being operatively connected in succession for fluid conduction and the inlets of the head receptacles in each group being connected to the said delivery means in parallel; whereby

upon release of fluid from the primary receptacle the fluid operated means directly connected to the delivery means in parallel are each acted upon by a portion of the fluid released from the primary receptacle, and each succeeding fluid operated means in a group is acted upon in succession both by a portion of the fluid released from the primary receptacle and the fluid released from the preceding receptacle or receptacles in the same group; the outlets of the last receptacles in each group being operatively connected to a common discharge line.

10. In combination, a fluid container having an opening and a closure for the opening, a body formed with a chamber, an operating member in the form of a piston in said chamber, an inlet for admitting an operating fluid into the chamber above the operating member to actuate the same, an opening member associated with said operating member, said opening member being operable by said operating member to open said closure, an outlet port normally closed off by the operating member from the space above the operating member and uncovered by movement thereof to release the operating fluid only after the opening of the closure member has been effectively completed, and a normally closed fluid conducting passage adapted to be opened by movement of the operating member to connect the space above the closure with the outlet, whereby the fluid released from the container may also be discharged through the outlet when the passage has been opened by movement of the operating member.

11. In combination, a fluid container having an opening and a closure for the opening, a body formed with a chamber, an operating member in the form of a piston in said chamber, an inlet for admitting an operating fluid into the chamber above the operating member to actuate the same, an opening member associated with said operating member, said opening member being operable by said operating member to open said closure, an outlet port normally closed off from the space above the operating member and uncovered by movement thereof to release the operating fluid only after the opening of the closure member has been effectively completed, and a normally closed fluid conducting passage adapted to be opened by movement of the operating member to connect the space above the closure with the outlet, whereby the fluid released from the container may also be discharged through the outlet when the passage has been opened by movement of the operating member.

DANIEL MAPES. 55
